John Howard Tabler,
INVENTOR.

By

Grace S. Beall,
ATTORNEY.

UNITED STATES PATENT OFFICE.

JOHN HOWARD TABLER, OF LANHAM, MARYLAND.

BUCKLE.

Specification of Letters Patent. Patented Feb. 20, 1917.

1,216,881.

Application filed June 22, 1916. Serial No. 105,181.

To all whom it may concern:

Be it known that I, JOHN HOWARD TABLER, a citizen of the United States, residing at Lanham, in the county of Prince Georges 5 and State of Maryland, have invented a Buckle, of which the following is a full and complete specification.

My invention is an improvement in buckles, and relates more especially to that 10 particular class of such devices in which the free end of the binding strap or webbing is secured to the attached buckle by frictional engagement therewith, leaving the strap free of the usual holes and permitting it to 15 be readily and accurately adjusted or tightly bound around the article to which it may be applied.

The primary object of my invention is to 20 provide a tongueless buckle of this general type for use in connection with a binding strap or webbing, whereby the latter may be easily and conveniently looped around an object, package, or several school books and the slack quickly taken up by simply pulling 25 upon the free end of said strap; the engagement of the coöperating parts being such in the present instance as to secure a firm and secure fastening which will not yield or give until the buckle is manipulated 30 to release the strap or relieve the binding action thereof.

A further object of my present invention is to so construct the buckle that when the 35 binding strap is tightened around the article or articles said buckle will lie flat against the same to be out of the way of catching into anything, and present a neat appearance.

These important objects, as well as other 40 advantages which will hereinafter appear, are attained by the particular arrangement and formation of the strap engaging cross-bars and connecting side pieces constituting the buckle, all as hereinafter fully described 45 and specifically claimed.

In the accompanying drawings:

Figure 1 is a perspective view illustrating the application of my improved buckle in connection with a book strap.

50 Fig. 2 is a side view of the buckle, connected to a binding strap or webbing.

Fig. 3 is a detail sectional view of the buckle, the connection of the binding-strap thereto being shown in dotted lines.

55 Fig. 4 is a detail plan view of the buckle.

Like numerals of reference indicate like parts in all the figures of the drawings.

In carrying out my invention the buckle is made of a single casting or in one piece to present opposite parallel side walls 6, 6, 60 similar in configuration and connected by three strap engaging cross-bars 7, 8, and 9, at the rear, intermediate portion, and front of the buckle, respectively; the cross-bar at the front having a lifting-tongue or lip 10 65 formed integrally therewith and projecting forwardly for convenience in manipulating the buckle for releasing the same, as hereinafter described. The location of these cross-bars with respect to each other and 70 to the lower edges of the side pieces forms one of the essential features of my present invention, whereby to insure a firm hold or grip on the free end of the strap or webbing and provide that the said buckle will lie 75 flat against the book or other article to which the binding strap or webbing is applied. To accomplish this the rear cross-bar 7 is a slight distance above the plane of the lower edges of the side pieces, corresponding approximately to the thickness of 80 the strap or webbing to which the buckle is applied, the lower edge of the front cross-bar 9 is on a horizontal plane with the axis of said rear cross-bar, and the lower edge of 85 the intermediate cross-bar 8 is on a plane with the axis of the front cross-bar; the cross-bars 8 and 9 being spaced only a short distance apart while the cross-bar 7 is located a greater distance from the adjoining 90 cross-bar 8. In the present instance, also, the front cross-bar is flattened on its inner side to present a plain bearing surface 9^a for increased frictional engagement with the strap or webbing and a rather sharp edge 95 9^b at the lower end of the friction surface, and the intermediate cross-bar 8 may be and preferably is flattened at its lower front side, as at 8^a.

The buckle or fastening device is intended 100 for use in connection with a strap either of leather or fabric possessing the required flexibility, but in practice I find it is more effective with a fabric strap, commonly known as webbing, the width of the strap or 105 webbing being equal to the space between the side pieces of the buckle, and of course the buckles are made of different sizes according to the different widths of webbing 110 that may be produced; for instance when

used as a fastening in connection with a book-strap the latter may be made of three-quarter-inch webbing and the width of the buckle between the side pieces thereof should 5 correspond, and when applied to a trunk-strap the webbing would probably be an inch and a half or two inches, according to the work or strain to which the strap and buckle may be subjected, the size and 10 strength of the buckle corresponding with the size of strap or webbing used.

In applying the buckle to the strap or webbing, designated 11 in the drawings, one end of said strap is permanently connected 15 to the rear cross-bar 7 by looping it around said cross-bar and riveting the terminal portion to the body directly in the rear of the cross-bar by a rivet 12, or any other form of attachment may be used.

20 In use the free end of the strap is passed from the forward end of the buckle below the lifting tongue or lip 10 up between the cross-bars 7 and 8, brought over the cross-bar 8 and passed forwardly in between the 25 body of the strap and lower edges of the cross-bar 9 and tongue or lip 10; the strap being then formed into a loop which may be readily slipped over the package or pile of books which may be then bound tightly together 30 by simply pulling on the loose end of the strap. Of course the threading of the strap, or passing it around the cross-bar 8 as hereinbefore described, may be done after the strap is passed around the package 35 or books, but by maintaining the outer or free end of the strap in looped engagement with the cross-bar 8, or the strap in operative position, as illustrated in Fig. 2, it may be more quickly manipulated in binding 40 or tying up books, &c. When the free end of the strap is pulled upon the frictional engagement of the strap with the peculiarly shaped cross-bars 8 and 9 will serve to firmly and securely hold the strap in its 45 adjustment, and the buckle will lie flat upon the books. In pulling upon the free end of the strap it will easily slip through the buckle until the strap is tightly bound around the books, and when the free end 50 is released the looped portion within the buckle holds tightly and is not affected by any strain or pull on the body portion of the strap which binds the books together,

the wide frictional surface 9^a and adjoining sharp edge 9^b coöperating with the 55 cross-bar 8 to effect a firm hold. In order to release the binding action of the strap it is only necessary to tilt the buckle upward and rearward by pushing a finger of the hand under the lifting-tongue or lip 10, 60 which is provided with an upturned outer end 10^a to facilitate the operation. When tilted upward in this manner the gripping action of the binding-edge 9^b is relieved, as well as the gripping action of the edge 8^b 65 of the cross-bar 8, permitting the strap to slip around the last mentioned cross-bar.

When the strap is pulled tight through the buckle the hold or grip is such that the looped and frictionally engaged portion will 70 not slip or yield as long as the pull of the body portion of the strap is longitudinally with respect to the buckle, and as there is no slip or yield to the strap or webbing there 75 is little or no wear on the webbing. Furthermore, inasmuch as the binding action is effected by reason of the pull on the body portion of the strap below the clamped portion of the free end of said strap the books 80 may be carried by the free end without releasing the buckle.

Having thus described my invention, I claim:

A buckle comprising opposite side pieces with straight lower horizontal edges, a rear 85 cross-bar extending between the side pieces a short distance above the lower edges thereof for the attachment of a strap to the buckle above said lower edges, a front cross-bar between the side pieces and located with its 90 lower edge on a horizontal plane approximating the axis of the rear cross-bar, said front cross-bar having a flattened inner side to provide an increased friction surface and an engaging-edge at the lower end thereof, 95 an intermediate cross-bar between the side pieces at a higher horizontal plane than the front cross-bar and located a short distance from the latter, and a lifting tongue projecting from the front of the buckle on a 100 plane with the front cross-bar.

JOHN HOWARD TABLER.
